UNITED STATES PATENT OFFICE

WILLIAM DUBILIER, OF NEW YORK, N. Y., ASSIGNOR TO DUBILIER CONDENSER CORPORATION, OF NEW YORK, N. Y., A CORPORATION OF DELAWARE

CONDENSER KIT

Application filed September 3, 1924. Serial No. 735,567.

This invention relates to an improved condenser kit; particularly a condenser kit for enabling one to determine quickly and accurately the capacity required by an electrical circuit.

An object of the invention is to provide a condenser kit having preferably the form of a convenient portable casing in which are removably mounted a number of separate condensers, the capacity of each of which is known, and which has suitable conductors and terminals for permitting all or any part of such condensers to be joined to an electrical circuit that is to be tested. While the kit is designed for radio circuits, the principle thereof is not limited to the radio field; but may be employed with circuits of any kind in which the exact capacity for efficient operation must be ascertained.

The nature of the invention is set forth in the following description taken with the accompanying drawings, whereon,

Figure 1 is a top view of a condenser kit according to my invention, showing the casing with the top removed; and

Figure 2 is a section along the line 2—2 of Figure 1, showing the casing provided with a top or cover in closed position.

The same numerals identify the same parts throughout.

In the particular description of what the drawings present, I employ the numeral 1 to indicate a casing such as a box of wood or any other suitable material, which is closed at the bottom, sides and ends and is provided with a hinged cover 2, at the top, that may be raised at will, and held shut by any suitable fastening device not shown. Within the casing is a plurality of condensers 3, the capacity of each of which is known, and these condensers are removably mounted in the casing in multiple with one another between a pair of parallel supporting members or bars of conductive material

4. These bars extend longitudinally of the casing and their opposite extremities are bent up as indicated at 5 and perforated to give passage to screws 6 which secure these bars in position in the casing 1. The heads of the screws 6 engage the extremities of the

bars 4 and pass through the casing, carrying on their outer ends washers 7 and binding nuts 8. At one end of the casing, the screws are of slightly greater length, so that thumb nuts 9 can be screwed upon them to fasten thereto the conductors of an electric circuit; these longer screws with their thumb nuts 9 constituting terminals or binding posts. The two bars 4 carry means in the form of clips 10 of conductive material, disposed in transverse alinement, each of the clips carried by one bar being opposite a similar clip carried by the other bar; the clips 10 being intended for detachably engaging the condensers 3, so that one or more of the condensers 3 can be removed at will; these clips each having a shank 11, the end 12 of which can be secured by soldering, or in any other feasible manner, to one of the conductor bars 4.

As indicated in the drawings, the clips 10 are U-shaped and the end of each arm of the clips is widened somewhat as indicated at 13. Each condenser 3 is of well-known construction and consists of a stack of sheets of conductive material separated by insulation with cover plates of insulation, if desired, on opposite faces of the stack, and with the opposite ends of each condenser having bearing plates 14. These bearing plates may be in the form of clamps of some conductive material such as metal, embracing the opposite ends of the body of the condenser, one of the clamps being in circuit with part of the sheets of conductive material, and thus forming one pole or terminal of the condenser; while the other clamp 14 is in circuit with the remaining conductive sheets, and thus constituting the other terminal of the condenser. Therefore, when a condenser is mounted in the kit by inserting its opposite ends bearing the clamps 14 between any two opposing clips on the bars 4 so that the clips detachably engage the bearing plates 14, the condenser is then at the same time electrically connected with the members 4 and can be placed in circuit with other electrical apparatus by joining conductors to the binding posts carrying the thumb nuts 9.

In practice, the capacities of all of the individual condensers 3 being known, one can determine by means of this kit the exact capacity required in a given circuit or at any point in a given circuit, to obtain the best results and most efficient operation, all of the individual condensers being in parallel; and the total capacity is, of course, the sum of the capacities of the separate condensers. An experimenter can readily determine by taking out some of the condensers and otherwise manipulating the kit, just what number of condensers should be included in the circuit and what should be the total capacity of the condensers so included, to make the circuit operate to the best advantage. As soon as the operator thus finds by trial after having taken out some of the individual condensers and inserting others, that the circuit is working properly, he can at once ascertain what capacity is demanded by the condition of the circuit simply by adding the separate capacities of the condensers which are left in circuit between the bars 4. The kit is thus of great utility and advantage for experimenting and testing, and because it permits the operator to find the exact capacity which any circuit needs in order to afford the mode of operation required.

Each of the clips being by virtue of the shank or stem 11 resiliently mounted upon the bars 4, the separate condensers can very easily be inserted and removed as occasion arises.

While the foregoing description sets out the best construction in which the principle of my invention can be embodied, I, of course, may vary the details to the full extent indicated by the broad meanings of the terms of the appended claims.

Having described my invention, what I believe to be new and desire to secure and protect by Letters Patent of the United States is:—

1. A condenser kit comprising a casing having a pair of conductor bars therein disposed parallel to each other, clips of conductive material in transverse alinement secured to said bars, and condensers having bearing plates of conductive material at opposite ends thereof and joined to opposite poles of the condensers, so that said condensers can be detachably engaged by said clips in contact with said plates to connect said condensers to said bars.

2. A condenser kit comprising a casing having a pair of conductor bars therein disposed parallel to each other, clips of conductive material in transverse alinement secured to said bars, and condensers having bearing plates of conductive material at opposite ends thereof and joined to opposite poles of the condensers, so that said condensers can be detachably engaged by said

clips in contact with said plates to connect said condensers to said bars, said clips being resiliently mounted on said bars.

Signed at New York, in the county of New York and State of New York, this 27th day of August, A. D. 1924.

WILLIAM DUBILIER.
